DESIGN FOR AN OPHTHALMIC MOUNTING

Vern W. Doty, Buffalo, N. Y.

Application November 15, 1933, Serial No. 49,734

Term of patent 14 years

To all whom it may concern:

Be it known that I, Vern W. Doty, a citizen of the United States, residing at Buffalo, in the county of Erie and State of New York, have invented a new, original, and ornamental Design for Ophthalmic Mountings, of which the following is a specification, reference being had to the accompanying drawing, forming a part thereof.

Figure 1 is a front elevation of the ophthalmic

mounting embodying my design. Figure 2 is a top plan view thereof showing fragments of the temples in broken lines. Figure 3 is a perspective view of one of the lens mountings.

I claim:

The ornamental design for an ophthalmic mounting, substantially as shown and described.

VERN W. DOTY.
